CLAIM

The ornamental design for a crisscut clover shape precious stone, as shown and described.

DESCRIPTION

FIG. 1 is a perspective view of a crisscut clover shape precious stone showing our new design;

FIG. 2 is a top view thereof;

FIG. 3 is a bottom view thereof;

FIG. 4 is a first elevational side view thereof, the opposite second, third and fourth side views being a mirror image thereof;

FIG. 5 is a first elevational side view thereof taken at an angle of 45° relative to the side views of FIG. 4, the opposite second, third and fourth angled side views being a mirror image thereof;

FIG. 6 is another perspective view of a crisscut clover shape precious stone of FIG. 1 with surface shading applied thereof;

FIG. 7 is another top view of FIG. 2 thereof;

FIG. 8 is another bottom view of FIG. 3 thereof;

FIG. 9 is another first elevational side view of FIG. 4 thereof, the opposite second, third and fourth side views being a mirror image thereof; and,

FIG. 10 is another first elevational side view of FIG. 5 thereof, taken at an angle of 45° relative to the side views of FIG. 4, the opposite second, third and fourth angled side views being a mirror image thereof.
